UNITED STATES PATENT OFFICE.

HOMER M. DAGGETT, JR., OF ATTLEBOROUGH, MASSACHUSETTS.

JEWELRY.

SPECIFICATION forming part of Letters Patent No. 279,351, dated June 12, 1883.

Application filed February 24, 1883. (No model.)

To all whom it may concern:

Be it known that I, HOMER M. DAGGETT, Jr., of Attleborough, in the county of Bristol and State of Massachusetts, have invented a new and useful Improvement in Manufacture 5 of Jewelry; and I do hereby declare that the following is a full, clear, and exact description of the same.

My invention relates to an improvement in 10 the manufacture of ornamental jewelry; and it consists, essentially, in an article of jewelry composed of a back-plate struck up from a plate to form a shallow body, and a thin plate of ornamental open-work secured just within 15 the raised edges of the body; further, in making the body and the face plate of contrasting colors; and, finally, in details of construction, more particularly hereinafter specified.

The object of the invention is to produce a 20 pleasing ornamental effect, not only from the configuration of the face-plate itself, but from the exhibition of the colored body or back through the openings in such face-plate.

The invention is illustrated in the accompanying drawings, in which Figure 1 is a plan or front view. Fig. 2 is a transverse section.

A represents the back or body plate, composed of gold, silver, or base metal, of any desired thickness. It is struck up from a suitable blank into the form shown, having a raised 30 edge or rim, *a*; or it may be formed in any

other manner well known to those skilled in the manufacture of jewelry.

B is a face-plate, composed of thin metal, preferably of a different color from the back plate. Any suitable open-work design may 35 be formed in this plate, and in addition to such design the solid portions may be chased or engraved, as desired. The plate B is secured by soldering, for instance, just within the raised rim of the back A, so that an open space is 40 left between the two plates. A very pleasing ornamental effect is produced not only from the configuration of the face-plate, but from the contrasting colors of the metal.

I have shown the device as applied to a 45 breastpin; but it is applicable to charms, lockets, brooches, and indeed to all forms of jewelry.

Having described my invention, I claim—

An article of jewelry composed of a solid 50 back or body having a raised edge or rim and an "open-work" face-plate secured to such rim so as to leave a space between the back and face plate.

In testimony whereof I have signed my 55 name to this specification in the presence of two subscribing witnesses.

HOMER M. DAGGETT, JR.
